UNITED STATES PATENT OFFICE

EVERETT H. BARNEY, OF SPRINGFIELD, MASSACHUSETTS.

ROLLER-SKATE FASTENING.

SPECIFICATION forming part of Letters Patent No. 319,666, dated June 9, 1885.

Application filed March 2, 1885. (No model.)

To all whom it may concern:

Be it known that I, EVERETT H. BARNEY, a citizen of the United States, residing at Springfield, in the county of Hampden and State of Massachusetts, have invented new and useful Improvements in Roller-Skate Fastenings, of which the following is a specification.

This invention relates to improvements in fastenings for roller-skates, the object being to provide, in combination with the pivoted finger-piece by which the screw-rod of metal clamp fastenings is operated, a cheap and convenient fastening for securing the heel end of the skate to the boot of the wearer.

In the drawings forming part of this specification, Figure 1 is a perspective view of a roller-skate having applied thereto heel-fastenings embodying my improvements. Fig. 2 is a view of the clamp-operating screw-rod and said fastening devices separate from the skate.

In the drawings, *a* is the screw-rod extending from the rear of the heel-plate *b* under the latter and engaging with the pivot-nut *c*, to which the sole-clamps *e e* are connected, the latter being operated in the usual way by turning said screw-rod.

At the rear end of the screw-rod *a* is pivoted the finger-piece *d*, having the central bar, *o*, therein. Said finger piece is adapted to be turned up against the heel when the sole-clamps are clamped, but is free to swing laterally on the rod *a*, and to be swung to a line with the latter, and it serves as means for

turning said rod and as a fastening-point for the ankle-strap *h*. The said strap *h* is passed through the finger-piece *d* around its central bar, *o*, as shown, and is provided with a suitable buckle or other fastening.

In putting on and fastening the skate the latter is placed against the sole and heel of the boot, the finger-piece and strap are swung rearwardly from the heel-plate, and by seizing the finger-piece the screw-rod is turned and the sole-clamps are operated. This having been accomplished, the finger-piece is turned up against the rear of the heel-plate, and the ends of the heel-strap are carried around the ankle of the skater (thereby holding up said finger-piece) and buckled together, thereby securely fastening the skate to the heel of the boot.

This construction of a heel-fastening obviates the usual attachment of straps and leather parts to the border *v* of the heel-plate, and provides a fastening that is simple and effective.

What I claim as my invention is—

The heel-fastening for roller-skates, consisting of the finger-piece *d*, pivoted on the end of the screw-rod *a*, and the ankle-strap *h*, attached to said finger-piece, substantially as set forth.

EVERETT H. BARNEY.
